CATHODE RAY TUBE

Jesse E. Brown, Chicago, Ill.

Application August 2, 1935, Serial No. 34,374

6 Claims. (Cl. 250—162)

The present invention relates to cathode ray tubes, and is particularly concerned with improvements in the method and apparatus of cathode ray tubes for the focusing of the cathode rays.

The conventional mode of focusing cathode rays in the prior art has been by means of residual gas within the tube. Such tubes are subject to many disadvantages, and it is one of the objects of the present invention to overcome the inherent defects of the devices of the prior art mentioned. For example, in the prior devices, the residual gas molecules become ionized on being struck by high velocity electrons, and the electron beam passes through the gas and lines its path with a layer of slow-moving positive ions, the field of which effects the desired concentration and focusing. The focusing of the beam, therefore, depends upon the amount of ionization and the quality and pressure of the gas.

Therefore, anything which affects the gas in the tube, such as temperature, progressive clean-up or pollution from occluded gas, alter the focusing. Furthermore, the negative cathode on a gaseous tube is subjected to the destructive effect of the bombardment of the positive ions.

Focusing in such tubes also depends upon the slow ions being more or less in equilibrium and the frequency of deflection can easily become so high that the focusing condition does not have time to re-establish itself after one deflecting impulse before the next deflecting impulse takes place, and some gaseous tubes will not focus satisfactorily at high frequencies.

Another disadvantage is that as the deflecting voltage passes through zero in a gaseous tube, a barely perceptible mark appears in the line on the screen, due to ions in the path between the deflecting plates, although this seldom causes any trouble except in the most exacting work.

One of the objects of the invention is the provision of a focusing means for cathode rays which operates independently of any residual gas and which may, therefore, be incorporated in tubes in which the residual gas is reduced to a minimum.

Another object is the elimination of the destructive effect of the positive ions on the negative cathode of cathode ray tubes by providing an improved method of focusing which does not require the presence of residual gas.

Another object of the invention is the provision of an improved method and/or apparatus for focusing cathode rays which operates upon principles analogous to those of lenses used for light

rays, and by means of which focusing can be controlled more accurately.

Another object of the invention is the provision of an improved method and/or apparatus for focusing cathode rays which are not affected by temperature, progressive clean-up, pollution by occluded gases or by other gaseous conditions in the tube.

Another object of the invention is the provision of a new system of electrostatic focusing of cathode rays, which is peculiarly adapted to high vacuum or hard tubes, and which is capable of sharper focusing than the devices of the prior art.

Other objects and advantages of the invention will be apparent from the following description and the accompanying drawings, in which similar characters of reference indicate similar parts throughout the several views.

Referring to the three sheets of drawings,

Fig. 1 is a fragmentary sectional view, showing a cathode ray tube with the envelope in section, and the elements of the tube in elevation, a part of the tube being broken away to indicate that the tube is of greater length than the part shown;

Fig. 2 is a similar fragmentary view of the lower elements of the tube of Fig. 1, with the elements shown in section, taken on the plane of a line determined by the axis of the tube;

Fig. 3 is an enlarged view of the filament and grid elements, the cathode and grid being shown in section;

Fig. 4 is an elevational view of the elements of a modified form of tube;

Fig. 5 is an elevational view of the same elements, with parts of the tube in section, taken on the plane of the line 5—5 of Fig. 4;

Fig. 6 is a top plan view of the structure of Fig. 4;

Fig. 7 is an enlarged sectional view of the filament and grid of the tube of Fig. 4;

Fig. 8 is an elevational view of the elements of a modified form of tube, shown in full size;

Fig. 9 is a fragmentary sectional view of the tube of Fig. 8, taken on the plane of the line 9—9 of Fig. 8, looking in the direction of the arrows;

Fig. 10 is a horizontal cross-sectional view taken on the plane of the line 10—10 of Fig. 9, showing the structure of the supporting device.

Referring to Figs. 1 to 3, 20 indicates the envelope of a cathode tube, which is usually provided with a lower tubular portion 21, a frusto-conical portion 22, and a curved face or head 23. The face 23 may be curved upon a radius which is taken at a point centrally located with respect to all of the deflector plates as being the average

point of deflection, and the curvature is also advantageous from the point of view of withstanding the pressure on the exterior of the tube caused by the atmosphere. The interior surface 5 of the glass face 23 is covered with a suitable fluorescent material, such as, for example, willemite. The lower part of the tube is usually provided with an inwardly extending glass support 24, in which all of the leads are sealed, and which 10 provides a support for the various wires which support the elements.

The cathode ray tubes constructed according to the present invention may be provided with any of the conventional forms of filaments, cathodes and grids. The tubes are preferably evacuated to the highest vacuum which can be accomplished, and the vacuum is enhanced by the use of a getter, which is indicated by the numeral 25. The degree of vacuum will naturally depend 20 upon the facilities available and the point to which it is economically advantageous to evacuate the tube, but the present devices effect a focusing of the rays without the use of any gas, and are, therefore, adapted to the "hardest" type 25 of tubes.

The inside wall of the glass envelope may be coated with a thin electrically conducting layer of suitable metal or form of carbon, a connection to which may be brought out by a vacuum tight 30 sealed wire through the glass wall. This coating may extend from the region opposite the first anodes 60 and 61 to any distance along the wall up to the fluorescent coating on the curved end of the envelope. This coating may be connected 35 to the same positive potential as the anode 39 or operated at higher or lower voltages than this anode. This coating prevents the accumulation of electric charges on the glass wall. It may also serve as a substitute for the high voltage anode 40 39, in which case all other parts and electrodes are disposed in the same way as pictured, but focusing is accomplished between this conductive coating on the glass wall and principally the anode indicated as 60. The theory of operation in this 45 case is identical to that described for the cylindrical anode illustrated and described and labelled 39.

Referring to Fig. 3, the supporting leads 26, 27 carried by the glass 24 may be utilized both for 50 the support of the filament 28 and as electric conductors. Leads 26, 27 may be provided with fixed collars 29, upon which rests the mica disc 30, through which the filament passes.

The collars 29 comprise small tubular metal 55 members formed with a radially extending flange 31 at one end, and they may be secured to leads by soldering or by merely de-forming the tubular portion with pliers or other clamping means until it clamps the wire lead upon which it is placed.

The filament 28 is preferably a non-inductive coil which is formed by bending a conductor of suitable length back upon itself and coiling it helically upon a mandrel so that for each coil having current passing in one direction there is 65 a corresponding adjacent coil having current returning in the opposite direction to neutralize the inductive effect of these coils. The respective turns of the coils are, of course, spaced from each other, and by means of an elongated coil of this 70 type a more sturdy filament may be made than one of shorter length, which would necessarily have to be thinner and more fragile in order to secure sufficient resistance for the voltages which are to be applied to the filament.

The cathode may consist of a nickel tube 32, one

flat end of which rests upon the mica disc 30, the tube being arranged in spaced relation to the filament, but close enough thereto to be heated, and it is supported by a nickel wire lead 33, which passes through the mica plate and aids in holding the cathode in definite position with respect to the filament and other parts. 5

The filament is preferably made of tungsten wire, and the cathode preferably made of nickel, which is coated with barium or strontium carbonate, in order to secure emission of electrons 10 from the cathode.

The grid 34 may consist of a cup-shaped nickel member having a cylindrical portion 35 and a flat end portion 36, which is provided with a 15 centrally located aperture 37. The aperture 37 restricts somewhat the flow of the electrons from the cathode, and may be of the usual size employed in tubes of the prior art.

The grid may also consist simply of a metallic 20 cylinder without the apertured capped end, this cylinder to be coaxial with the cathode in the same manner as described and illustrated for the conventional grid.

The grid is carried also by the mica disc 30, and 25 is held in place by being welded to a nickel lead wire 38, which also preferably passes through the mica disc.

The tube is preferably provided with an accelerating cylindrical anode 39, and with the pairs 30 of deflector plates 40, 41, 42 and 43, arranged so that the beam will pass between the plates of each pair, and the plates of each pair being arranged at right angles to the plates of the other pair. 35

The accelerating anode 39 may comprise a tubular member of nickel, which is supported by means of the mica discs 44, 45. The anode 39 has welded to it or otherwise fixedly secured thereon a pair of wire rings 46, 47, which serve 40 as shoulders for engaging one side of each of the mica plates. The leads 48, 49, which comprise relatively stiff nickel wires, and are used as the leads for the deflector plates 41 and 48 respectively, are fixedly secured in the glass supporting portion 24, and pass upward parallel to each other, but spaced from the other elements of the tube, and pass through the mica discs 44, 45. 45

Mica discs 44, 45 may be secured to these leads 50 and others by additional ferrules 29 of the same type described with respect to the filament, the ferrules being clamped on the wires on each side of the mica discs 44, 45, so as to clamp the discs between the flanges of the ferrules. 55

The ferrules are so arranged upon these leads that the mica discs engage the wire shoulders 46, 47 and thereby confine them between the mica discs and secure the accelerating anode 39 to the mica discs, which, of course, have apertures for 60 passing the anode. Additional leads 50 and 51 also extend through the mica discs 44, 45, to which they are secured in the same manner by ferrules 29, and carry at their upper ends the deflector plates 42, 43. At their lower ends the 65 leads 50, 51 also are connected to suitable wires, as are all of the leads, which wires are sealed in the glass support 24 in such manner as to provide a gas-tight joint between the wire and the glass. The leads 48 to 51 are preferably provided with insulators comprising the glass tubes 52 to 55, of suitable length, to cover the leads from the upper mica disc 44 to the point where the leads are bent in and welded to the deflector plates. 70 75

The deflector plates may comprise flat, nickel, plates, the plates of each pair being of equal area. As the deflection is greater toward the upper end of the tube, the lower plates 42, 43 may be tapered downward to a width corresponding substantially to the diameter of the accelerating anode 39 to save material, and the plates 40, 41 may be made slightly wider, in order to more certainly cover the range of movement of 10 the deflector beam.

All of the deflector plates are secured together in the same manner, and therefore the securing means will be described with respect to only one pair of plates. For example, plate 41 is provided 15 with a pair of laterally projecting wires 56, 57, which are welded to the upper portion and outside of the plate. The outer ends of these wires are secured in the glass insulators 58, 59, which comprise substantially cylindrical portions of 20 glass, in which the wires are embedded.

The plate 40 is likewise provided with wires which are embedded in the insulators 58, 59, and plates 40, 41 are thus secured in spaced relation to each other at their upper edges. The leads 25 46, 49 serve to secure the plates at their middle or lower portions, and the plates are thus held substantially parallel to each other.

It has already been pointed out that plates 42, 43 are arranged at right angles to plates 40, 41, 30 the plates 42, 43 being also supported by their leads and by suitable wires and glass insulators in spaced relation and parallel to each other.

The cathode ray tubes are also preferably provided with focusing anodes, which may comprise 35 the apertured discs 60, 61. In some embodiments of the invention, one of the apertured focusing discs 61, which is nearest to the filament, may be omitted, as I have constructed tubes without it which work satisfactorily, but considerable 40 difficulty is experienced in the alignment of the elements of these tubes, and the first or lower disc facilitates the manufacture by making it easier to make a commercial tube that will work. Furthermore, there is less loss of electrons by spreading 45 when both discs are employed, and therefore I prefer to use the two focusing anodes. The second disc 60 is essential.

The first anode labeled 61 may be used as a 50 control element to vary the quantity of the electron stream focusing through it and hence varying the brilliancy of fluorescence. This may be accomplished by simply varying the normal potential applied to it. Alternating currents may be superimposed on the normal direct voltage 55 connected to this anode, which will cause its density of the electron beam to vary in accordance with the magnitude and frequency of the impressed A. C. By this means the tube can be modulated for various purposes, such as 60 television.

These anodes may consist of nickel discs which are provided with circular apertures 62, 63, similar in size to the aperture in the grid. Holes as 65 large as 0.1 inch have been used, and the others, range from 0.025 to 0.25 inch. The sizes of apertures mentioned herein are not to be regarded, however, as definite limits. The smaller apertures may assist in confining the beam to smaller 70 limits in the course of its travel, but they also increase the difficulties of alignment of the elements of the tube, since all of the elements must be arranged substantially along the axis of the tube. The focusing anodes or discs 60, 61 must 75 be arranged substantially parallel to each other

and at a predetermined distance from each other or from the source of electrons.

I have termed the focusing anodes 60, 61 discs, although, in fact, they are shown in Fig. 2 as being substantially cup-shaped, each focusing anode having a cylindrical portion 64, which is mounted upon a glass tube 65. The anodes 60 and 61 are, in fact, discs in so far as their electrical properties are concerned, since the glass tube 65 effectively shields all parts of them except 10 the flat or disc surface from the electron beam. The only action of these anodes on the beam is that of two discs. The cylindrical portion 64 is, however, insulated from the electron beam by the glass tube 65, and is merely included as a 15 support for the focusing anode discs 60, 61. Each of these cylindrical portions is welded to laterally extending wires, which in turn are welded to the same leads 66, 67, so that when the focusing anodes are both at the same potential, only one 20 of the leads 66, 67 need be brought out of the tube.

The arrangement of the focusing anode or anodes with respect to the other elements is one of the most important features of the present 25 tube, and I have discovered that there is a definite relation between the voltage which is applied to the accelerating anode or cylinder and the voltage applied to the focusing discs, which depends upon the distance between the upper focusing disc 60 and the source of electrons. For example, when a potential of 2,000 volts is applied to the accelerating anode or cylinder 39, and a potential of 300 volts is applied to the focusing discs 60, 61, the disc 60 is approximately one and 30 one-quarter inch from the source of electrons, and with these voltages the beam is focused 35 sharply upon the fluorescent screen of the face 23 by means of focusing discs.

The foregoing figures are not to be regarded 40 as mathematically accurate, as it is my custom to first construct the tube with its focusing disc at a predetermined spacing to the other elements, and then experimentally determine the exact 45 ratio of voltages or the voltages which are applied to the focusing disc and an accelerating anode, to effect the best focusing. I have discovered that when the spacing between the focusing anode and source of electrons is changed, the voltage applied to the focusing anodes and 50 accelerating anode should also be changed accordingly, and the relation between these parts and the potentials is analogous to the spacing of the lens of a light ray system. Thus, predetermined voltages and spacing produce a focus on 55 the screen at a certain distance, and if the tube is changed in size the factors of applied voltages and anode spacing must be changed accordingly, primarily the latter.

The focusing is independent of the presence 60 of any residual gas, and therefore eliminates the disadvantages enumerated above, of the prior devices which employ residual gas for focusing, and tubes constructed according to the present invention have a life which corresponds to the life 65 of the best audion tubes. The usual potentials are applied to the grid, the filament, and the deflector plates, and the present tubes may be utilized in any manner in which the cathode tubes of the prior art may be utilized, for television, 70 etc.

Referring to Figs. 4 to 7, this is a modification 75 in which a different type of filament is employed and in which the different modes of support are employed for several of the elements.

Referring to Fig. 7, the filament 68 comprises a tungsten filament, bent in the form of a loop, and having a small nickel rod disc or wire 69 welded to the ends of the two wires forming the filament loop. The nickel disc 69 is coated with barium or strontium carbonate, in order to provide for the emission of electrons therefrom, and the source of the electrons and the filament are covered by the grid 34.

In this case the focusing discs 60 and 61 are again supported upon a glass tube 65, which in turn is supported by means of a metal tube 70 embracing the glass tube. The metal tube 70 is welded to the rectangular wire brackets 71 at each side, which brackets have downwardly protecting wire ends 72 that are embedded in the glass insulators 73 carried by wire supports 74.

Referring to Figs. 8 to 10, this is another modification, in which many of the elements may be the same as described with respect to Figs. 1 to 3. The deflector plate leads 48, 49, 50 and 51 are covered with the glass tubes extending from a point adjacent the deflector plates to a point below the top of the grid.

In order to support these last tubes in place, each of the leads may be provided with a ferrule 5 clamped on the wire above the tube, and a ferrule 76 clamped on the wire below the tube. The tubes and leads 50—54 are secured to the accelerating anode 39 by means of a pair of metal bands or bands 77, 78, which may comprise strips of sheet metal, such as nickel, having their ends welded together and shaped complementarily to the opposite outer outline of the insulating glass tubes on leads 50—54, and the accelerating anode 39.

In other words, each band has four flat portions, each of which may be welded or otherwise cured to the accelerating anode 39, and each band has four partially cylindrical portions 80, which frictionally grip the glass tubes which surround the leads 50—54. The lower ends of these bands may be connected to the usual wires that are soldered in the glass supporting base 24. In this case the accelerating anode and the upper focusing disc are mounted in spaced relation to each other by the angle shaped wires 81—84. One end wire 81 is secured to the accelerating anode 39 band 78 by welding, and the other end is embedded in insulator body 85 of glass, lava or other insulating material. The other wire 82 is secured in like manner to the glass insulator body 85 and the cylindrical flange of the focusing disc 60. It will thus be observed that I have invented a variety of improved forms of cathode ray tubes in which the focusing of the beam does not depend on the presence of residual gas, so that the tube may be evacuated as much as possible to eliminate undesirable effects of residual gas. The present tube is, so far as I am aware, the first one in which the distance between the focusing and accelerating anode combination and the grid bears direct relation to the distance from the accelerating anode at which a focus will be obtained, or which the spacing of the focusing disc from the source of electrons bears any relation to the potentials applied and to the place at which a focus of the electron beam takes place. By means of my improved method and apparatus the cathode rays may be focused more sharply and accurately, and the present tubes are admirably suited for exacting work in television, oscilloscopes, etc.

While I have illustrated and described a pre-

ferred embodiment of my invention, many modifications may be made without departing from the spirit of the invention, and I do not wish to be limited to the precise details of construction set forth, but desire to avail myself of all changes within the scope of the appended claims. 5

Having thus described my invention, what I claim as new and desire to secure by Letters Patent of the United States, is:

1. A cathode ray tube adapted to have its cathode rays focused, comprising an envelope evacuated to such a high vacuum that there are substantially no visible ionization effects, a source of electrons within said envelope and located at one end of said envelope, a translucent fluorescent screen carried by said envelope and located at an opposite end of said envelope, a focusing anode comprising an apertured electrical conducting diaphragm, located between said source and said screen, with its aperture in alignment with a beam of electrons from said source, said diaphragm being in a plane at substantially right angles to the direction of said beam, and an accelerating anode of the tubular type constructed of electrically conducting material and located between said focusing anode and said screen, said accelerating anode having a substantially larger diameter than the aperture in said diaphragm and having its axis in substantial alignment with said source and the aperture in said focusing anode, 30 said diaphragm and tubular electrode being located close together but out of contact with each other and both being at a greater distance from said source of electrons than they are spaced from each other, said tube including means for supporting said anodes in said envelope and insulating said anodes from each other, the spacing of said focusing anode from said source depending upon the potential gradient adapted to be maintained between said anodes to cause the electron 40 stream to be projected toward said screen and to produce a focus of the beam at a sharply defined point on said screen. 35

2. A cathode ray tube adapted to have its cathode rays focused, comprising an envelope evacuated to such a high vacuum that there are substantially no visible ionization effects, a source of electrons within said envelope and located at one end of said envelope, a translucent fluorescent screen carried by said envelope and located at an opposite end of said envelope, a focusing anode comprising an apertured electrical conducting diaphragm, located between said source and said screen, with its aperture in alignment with a beam of electrons from said source, said diaphragm being in a plane at substantially right angles to the direction of said beam, and an accelerating anode of the tubular type constructed of electrically conducting material and located between said focusing anode and said screen, said accelerating anode having a substantially larger diameter than the aperture in said diaphragm and having its axis in substantial alignment with said source and the aperture in said focusing anode, said diaphragm and tubular electrode being located close together but out of contact with each other and both being at a greater distance from said source of electrons than they are spaced from each other, said tube including means for supporting said anodes in said envelope and insulating 70 said anodes from each other, the spacing of said focusing anode from said source depending upon the potential gradient adapted to be maintained between said anodes to cause the electron stream to be projected toward said screen and to produce 75

a focus of the beam at a sharply defined point on said screen, and a modulating electrode comprising a tubular metal member having one of its ends covered with an apertured disc and located 5 between said focusing diaphragm and the source of electrons.

3. A cathode ray tube adapted to have its cathode rays focused, comprising an envelope evacuated to such a high vacuum that there are substantially no visible ionization effects, a source 10 of electrons within said envelope and located at one end of said envelope, a translucent fluorescent screen carried by said envelope and located at an opposite end of said envelope, a focusing 15 anode comprising an apertured electrical conducting diaphragm, located between said source and said screen, with its aperture in alignment with a beam of electrons from said source, said diaphragm being in a plane at substantially right angles to the direction of said beam, and an accelerating anode of the tubular type constructed 20 of electrically conducting material and located between said focusing anode and said screen, said accelerating anode having a substantially larger diameter than the aperture in said diaphragm 25 and having its axis in substantial alignment with said source and the aperture in said focusing anode, said diaphragm and tubular electrode being located close together but out of contact with 30 each other and both being at a greater distance from said source of electrons than they are spaced from each other, said tube including means for supporting said anodes in said envelope and insulating said anodes from each other, the spacing 35 of said focusing anode from said source depending upon the potential gradient adapted to be maintained between said anodes to cause the electron stream to be projected toward said screen and to produce a focus of the beam at a 40 sharply defined point on said screen, said accelerating electrode comprising a metal cylinder, and said tube having a layer of conducting material carried by its inner surface from a point adjacent said screen to a point adjacent the 45 source of electrons, said conducting layer being adapted to be charged with a positive potential.

4. In a focusing arrangement for cathode ray tubes, the combination of a supporting base with a plurality of leads carried by said base, certain 50 of said leads being connected to and supporting a source of electrons, certain other of said leads extending beyond said source of electrons and supporting a pair of oppositely disposed metal caps, said caps being mounted upon an insulating 55 sleeve to maintain said caps in alignment, and said caps being provided with aligned apertures, another lead carried by said base and connected to and assisting in the support of an accelerating cylinder, said accelerating cylinder being insulated from said caps and being located 60 in substantial alignment with said caps, the farthermost of said caps being spaced from the source of electrons a predetermined distance, depending upon the voltage adapted to be applied 65 to said accelerating electrode and said caps, to effect a focusing of the cathode rays, and oppo-

sitely disposed insulating connections between said accelerating electrode and the adjacent metal cap for maintaining the alignment of electrode and cap, a pair of metal bands carried by said accelerating electrode and embracing a plurality of insulating tubes, other leads in insulating tubes, and supporting a pair of electrostatic deflecting plates in substantial alignment with said accelerating electrode.

5. In a focusing arrangement for cathode tubes, the combination of a supporting base with a plurality of leads carried by said base, certain of said leads being connected to and supporting a source of electrons, certain other of said leads extending beyond said source of electrons supporting a pair of oppositely disposed metal caps, said caps being mounted upon an insulating sleeve to maintain said caps in alignment, said caps being provided with aligned apertures, another lead carried by said base and connected to and assisting in the support of an accelerating cylinder, said accelerating cylinder being insulated from said caps and being located in substantial alignment with said caps, the farthermost of said caps being spaced from the source of electrons a predetermined distance, depending upon the voltage adapted to be applied to said accelerating electrode and said caps, to effect a focusing of the cathode rays, a pair of metal bands carried by said accelerating electrode and embracing a plurality of insulating tubes, other leads in said insulating tubes, and supporting a pair of electrostatic deflecting plates in substantial alignment with said accelerating electrode and auxiliary insulating connections between electrostatic deflecting plates for holding said plates in predetermined spacing and relation to each other.

6. In a focusing arrangement for cathode tubes, the combination of a support with a plurality of leads supported thereby, a source of electrons carried by certain of said leads and a modulating electrode comprising a cylindrical member having its outer end capped with an apertured diaphragm, said aperture being aligned with the source for emission of electrons, a pair of cylindrical cap-shaped and oppositely disposed and mounted on an insulating tubular member carried by other predetermined leads, said latter caps being provided with apertures in alignment with the source of electrons and a tubular accelerating electrode located in alignment with said tubular insulating member and carried by other predetermined leads, said latter predetermined leads passing through a pair of insulating discs secured to said leads, and said discs being engaged on the opposite sides of shoulders carried by said accelerating electrode, certain of said latter predetermined leads extending beyond said accelerating electrode and supporting pairs of oppositely disposed electrostatic deflecting plates, said pairs being arranged transversely to each other in a substantial alignment with said accelerating electrode and source of electrons.

JESSE E. BROWN
